C. M. YODER

OPERATING MECHANISM

Filed June 6, 1922

FIG. 1

UNITED STATES PATENT OFFICE.

CARL M. YODER, OF CLEVELAND, OHIO, ASSIGNOR, BY MESNE ASSIGNMENTS, TO
BASTIAN-MORLEY CO., OF LA PORTE, INDIANA, A CORPORATION OF INDIANA.

OPERATING MECHANISM.

Application filed June 6, 1922. Serial No. 566,345.

To all whom it may concern:

Be it known that I, CARL M. YODER, a citizen of the United States, residing at Cleveland, in the county of Cuyahoga and State of Ohio, have invented certain new and useful Improvements in and Relating to Operating Mechanisms, of which the following is a specification.

This invention relates to an operating mechanism, particularly adapted for use in connection with a thermostat, whereby a device, such as a valve may be efficiently controlled. The invention may be advantageously applied for the purpose of controlling the supply of fuel to a heating device or a heating medium either of which may be utilized to maintain a fluid in a confined space, such as a tank, at a substantially uniform temperature.

One object of the invention is to provide an improved operating mechanism having an actuating member which operates substantially in an endwise direction axially of the valve opening to unseat a valve element and permit the seating thereof, whereby the valve element may be readily actuated to properly control the flow of the fuel or heating medium.

Another object of the invention is to provide an improved valve operating mechanism, having a coiled spring interposed between the plunger or thrust member of the mechanism and the valve element, arranged to be compressed in the movement of the plunger or thrust member to actuate the valve element, whereby the latter will be unseated with a relatively quick movement.

Other objects of the invention will be obvious to those skilled in the art to which my invention relates from the following description taken in connection with the accompanying drawings, wherein—

Fig. 1 is a longitudinal sectional view of a thermostat valve control mechanism embodying my invention.

Fig. 2 is a view similar to Fig. 1, but showing the valve element in an operated position.

Fig. 3 is a perspective view of one of the main operating levers.

Fig. 4 is a perspective view of the other main operating lever.

Fig. 5 is a perspective view of the supplemental lever.

Fig. 6 is a perspective view of the link

which is connected to one of the main operating levers and the supplemental lever.

Fig. 7 is a vertical sectional view of the plunger and spring carried thereby.

Fig. 8 is a fragmentary side elevation of the parts shown in Fig. 1, but showing movement of the thrust member upwardly and compression of the valve operating spring prior to the unseating of the valve.

Fig. 9 is a perspective view of the operating levers.

The present invention is an improvement upon the operating mechanism disclosed in my Patent 1,367,935, granted February 8, 1921, to which reference may be made to illustrate and disclose one useful application of my invention. In view of the disclosures in such patent, it will not be necessary to herein disclose and describe the apparatus in such application.

In the drawings 6 indicates a fuel supply pipe, preferably for gaseous fuel, leading to a burner (not shown), such pipe being arranged adjacent to a tank 1 containing water that is to be heated so that the operating mechanism embodying my invention and the thermostat elements, indicated as an entirety at 13, 14, can be operatively connected with the thermostat elements disposed within the tank 1, as shown. The valve mechanism 7 is interposed in the pipe 6 so as to control the flow of gas therethrough to the burner. Of this mechanism, 8 indicates a casing shaped and constructed in any well-known manner to form a chamber 8^a and pipe sections 8^b, 8^c, to which the ends of the pipe 6 (see Figs. 1 and 2) are connected. 9 indicates an annular rim or flange extending inwardly from the internal wall of the pipe section 8^b to form a valve opening 9^a. The outer circumferential edge of the flange 9 is ground or otherwise finished to form a seat 9^b for a valve element 10. Preferably the seat 9^b is ground to a relatively fine edge. The chamber 8^a is closed on one side by a cap 8^a'. The cap is preferably provided with screw threads for engagement with screw threads on the inner wall of the casing 8. The valve element 10 preferably comprises a ball of solid material normally resting on the seat and maintained thereon by its weight and the pressure of the gas within the supply pipe 6. 11 indicates guides extending inwardly from the inner wall of the pipe section 8^b. The pipe section 8^b is en-

75

80

105

110

larged to form sufficient space for the flow of gas around the valve element. At one side, the casing 8 is provided with a plug or head 12 preferably formed integrally with the walls of the casing. At its outer end the plug 12 is provided with screw threads to fit a screw threaded opening in the side wall of the tank 1. The screw threaded portion of the plug 12 may be reduced to form 10 a shoulder 12^a which bears against the wall of the tank 1 to provide a liquid tight joint when the plug 12 is connected with the tank 1 in the manner shown.

12^b indicates an opening extending 15 through the plug 12 and adapted to receive the inner ends of the thermostat elements 13, 14. The element 13 preferably comprises a section of tubing formed from copper or other material capable of readily expanding 20 under the influence of heat. The inner end of the tube 13 fits tightly within the opening 12^b, preferably extending to the inner end thereof. The tube 13 may be soldered or otherwise secured in the opening 12^b. The 25 element 14 is preferably formed from some material, such as porcelain which is not to any substantial extent affected by temperature changes. At their outer ends, the elements 13, 14, are connected together as shown 30 at 15 in any suitable manner so that the expansion and contraction of the tube 13 will move the element 14 endwise in one direction or the other accordingly as the temperature of the water surrounding the tube 35 13 rises or falls. The connection 15 preferably comprises a plug 15^a, which closes the outer end of the tube 13. The plug 15^a has a screw threaded opening through it, and a rod 15^b, which is fixed to the element 14, extends 40 through the opening. The rod 15^b is provided with screw threads to fit the screw threads of the opening in the plug 15^a and its outer end is formed with a suitable slot to receive a tool by which the element 14 45 can be turned, such operation serving to adjust the element 14 longitudinally of the element 13. The outer end of the tube 13 may be secured to the plug 15^a in any desired manner. Since the inner end of the 50 element 13 is fixed to the casing 8 and its outer end is connected to the outer end of the element 14, it will be understood that when the temperature of the medium surrounding the element 13 rises, the latter expands and moves the element 14 endwise toward the right, as viewed in Fig. 1; on the other hand when the temperature of the medium falls, the element 13 contracts and moves the element 14 endwise in the opposite direction. The connection 15 is preferably of an air or gas and water tight character.

16 indicates the valve operating devices 60 interposed between the valve 10 and thermostat elements 13, 14, and arranged in the

chamber 8^a. Of these devices, 16^a indicates a main lever pivotally mounted in the chamber 8^a in any suitable manner, but preferably by a horizontal shaft 16^b, the opposite ends of which are supported in the opposite side walls of the casing 8. The lever 16^a is preferably bell-shaped, having arms 16^{a'}, 16^{a''}. 70

The arm 16^{a'} of the lever 16^a preferably comprises a body portion 16^x having an opening 16^{x'} through it and a pair of spaced members 16^c arranged to support at their free ends a pin or shaft 17, the purpose of which will be later described. 18 indicates a second lever pivoted to the free end of the arm 16^{a''} of the lever 16^a by a pivot pin 18^a. 80 The lever 18 is preferably bell-shaped, having arms 18^{a''}, 18^{a'}, the latter comprising two spaced members which support at their free ends a shaft or pivot 19, to be later referred to. At 19^a, the lever 18 is cut away to receive the arm 16^{a''} of the lever 16^a, to which the lever 18 is fulcrumed by the shaft or pin 18^a. The levers 16^a and 18 are so arranged relative to the axis of the opening 12^b that the inner end of the thermostat element 14 will engage the lever 16^a at a point between its pivot 16^b and the pivot 18^a between the lever 16^a and lever 18. When the thermostat element moves toward the left, as viewed in Fig. 2, it will tend to swing both levers 16^a, 18, about the pivot 16^b, but due to the provision of an abutment 20 in the path of movement of the lever arm 18^{a''}, the movement of the thermostat element 14 will result in swinging the free ends of the lever arms 16^{a'}, 18^{a'}, away from each other. On account of the length of the lever arms 16^{a'}, 18^{a'}, as compared with the length of the arms 16^{a''}, 18^{a''}, respectively, a short movement of the latter arms 105 will cause considerable movement of the arms 16^{a'}, 18^{a'}. As these arms move away from each other simultaneously, the rate of movement of their free ends relative to each other is materially increased. 110

21 indicates a supplemental lever mounted on the shaft or pin 19 between the free ends of the spaced members constituting the arm 18^{a'}, said lever 21 extending inwardly or toward the pivot 16^b so that its free end may move within or between said spaced members. 22 indicates a link pivotally connected at one end to the lever arm 16^{a'} by means of the shaft 17 and at its opposite end pivotally connected by means of a pin or shaft 22' to the lever 21, so that when the arms 16^{a'}, 18^{a'} move away from each other, the link 22 will serve to swing the lever 21 about the pivot pin 19. As shown, the pin 22' is arranged relatively close to the pivot pin 19 so that slight movement of the arms 16^{a'}, 18^{a'} relative to each other will swing the free end of the lever 21 through a relative long arc. 120

22^a indicates a plunger or thrust member 130

pivottally connected at its lower end to the lever 21 so as to be actuated thereby and extending upwardly whereby it may lift or unseat the valve element 10, when the lever 21 is operated in the manner to be later described. The free end of the lever 21 is preferably bifurcated, as shown in Fig. 5 and the lower end of the plunger 22^a is reduced (see Fig. 7) to fit between these bifurcations. The plunger or thrust member 22^a preferably extends through the opening 16^x in order that the walls of the opening may guide the plunger or thrust member and cause it to move in an endwise direction substantially axially of the valve seat as it operates upwardly and downwardly. With these parts constructed and arranged as just described, operation of the levers 16^a, 18, away from each other due to movement of the element 14 toward the left, will simultaneously cause the pivot 17 to move upwardly and the arm 18^a to swing downwardly; due to this simultaneous operation, the thrust member 22^a will be actuated upwardly. When the element 14 moves toward the right, due to rise in temperature of the medium in the tank 1, it permits the thrust member 22^a and the levers 21, 16^a and 18 to swing downwardly, due to their weight, to normal position. If the thrust member 22^a were actuated in the manner already described, it would engage the valve element 10 and lift it from its seat; and then permit the valve element to seat itself as the thrust member moves downwardly. But I prefer to interpose between the valve element 10 and the thrust member 22^a a spring 23, whereby the pressure of the fuel acting on the valve element may be utilized to compress the spring 23 as the thrust member moves upwardly so that the spring may be compressed or placed under tension and caused to unseat the valve element 10 with a relatively quick movement. The spring 23 is connected at its lower end to the thrust member 22^a so as to move upwardly and downwardly therewith. The spring 23 is preferably coiled and shaped to form a pocket for the valve element 10, its upper end being of a size to fit within the valve seat and to engage the valve element at points substantially concentric to the axis of the valve seat.

The valve element 10 is held to its seat by its weight and also by the pressure of the fuel flowing in the pipe 6. As the thrust member 22^a moves upwardly, it compresses the spring 23 against the combined resistance of the weight of the valve element and pressure of the fuel (see Fig. 8), until the tension of the spring overcomes such resistance, whereupon the spring 23 with a relatively quick action, will unseat the valve element and allow a full supply of fuel to pass the valve to the burner.

This operation will insure proper and immediate ignition of the burner from its pilot and also prevent waste of fuel.

The spring 23 is preferably connected to the thrust member 22^a in a detachable manner. For this purpose, its upper end is formed with a screw threaded opening to receive a screw 22^b. The head of the screw is provided with a collar 22^c, which co-operates with a washer 22^d held on the upper end of the thrust member 22^a by the head of the screw 22^b, to detachably engage the end convolution of the spring 23 and thus secure it in position. The head of the screw 22^b may be provided with a slot to receive a tool whereby it may be readily operated to clamp the spring 23 in position or release it.

The abutment 20 is preferably adjustable to different positions so that the temperature of the water in the tank 1 can be kept at any desired temperature within certain limits. In other words, by moving the inner end of the abutment 20 toward or from the lever arm 18^a, the latter may be caused to engage the abutment at any desired time in the forward movement of the levers 16^a, 18, and thus regulate the opening and closing of the valve 10. For this purpose the abutment 20 preferably comprises a rod provided with screw-threads 20^a which fit a screw-threaded opening 8^d formed in the casing 8. The opening 8^d is preferably formed in a thickened portion of the casing wall so that a long screw-threaded opening therethrough may be provided to prevent the escape of gas. To the other end of the rod 20 is fixed a hand or pointer 20^b, which is movable relative to a suitable scale or graduations on a plate 8^e, whereby the temperature of the water can be intelligently controlled. The plate 8^e is preferably formed integrally with the casing 8. As it is desired to prevent molesting with the temperature control device 20, the pointer 20^b, which may serve as the means for adjusting the abutment 20, is inclosed by a cover 24. The cover 24 may be held in place by a plurality of screws 24^a.

From the foregoing description it will be seen that the levers 16^a, 18, link 21 and lever 22 are so connected together for co-operation that relatively slight movement of the thermostat element 14 will transmit relatively long and quick movement to the thrust member 22^a, so that the valve 10 will be actuated to unseat and seat the valve due to relatively minute changes in temperature of the medium in the tank 1. The leverage ratio in a system of levers embodying my invention is so large that I am enabled to successively control the supply of a heating medium or the supply of fuel to a burner for heating a room or rooms simply by supporting the thermostat elements therein.

The levers 16^a and 18 are so shaped that

they and the lever 21, link 22 and thrust member or plunger 22^a can be correlated for operation in a relatively small chamber; further, the construction of these levers is such that each pivot for and between them, as well as the link 22 and thrust member 22^a is supported in bearings at its opposite ends.

To those skilled in the art to which my invention relates many changes in construction and widely differing embodiments and application of the invention will suggest themselves without departing from the spirit and scope thereof. The descriptions and disclosures herein are purely illustrative and 15 are not intended to be in any sense limiting.

What I claim is:

1. In a mechanism of the class described, the combination with a casing having a valve opening through which fluid passes, and a 20 valve element for said valve opening, of means for operating said valve element, said operating means comprising a plurality of connected multiplying levers, a thermostat element engaging one of said levers and thrust means carried by another lever, said thrust means having a coiled spring extending in a direction axially of said valve opening and mounted to swing relative to said last mentioned lever, whereby said spring 25 remains in said axial position and moves axially into engagement with and operates said valve element during swinging movement of said lever.

2. A mechanism as claimed in claim 1 in 35 which the valve element is guided vertically and co-acts through its engagement with said spring to maintain the latter in substantially axial alignment with said valve opening while being moved vertically to open and close said valve element.

3. A mechanism as claimed in claim 1 in 45 which said thrust means comprises a stem pivoted at its lower end to said lever and normally disposed in axial alignment with said valve opening, said spring extending beyond the free end of said stem, whereby it maintains a substantially vertical position axially of said valve opening while operating to open and close the latter.

50 4. The combination with a casing, having a valve opening through which fluid passes, and a valve for said valve opening, of means for operating said valve, said operating means including two members one operatively connected to the other and each having operative connection with said casing, a lever carried by one member, a link between the other member and said lever, a thrust member arranged to be actuated by 55 said lever to unseat said valve, and means for guiding said thrust member in an endwise direction.

5. A mechanism as claimed in claim 1 in 60 which said thrust means comprise a pivoted stem, said spring surrounding said stem and

swingable therewith and extending beyond the free end of said stem, whereby said stem and spring are free to maintain a substantially vertical position while being moved vertically by said connected levers.

6. The combination with a casing having a valve opening through which fluid passes, and a valve for said valve opening, of means for operating said valve, said operating means including two members one operatively connected to the other member and each having operative connection with said casing, a lever carried by one member, a link between the other member and said lever, and a thrust member arranged to be 70 actuated by said lever to unseat said valve, one of said members being formed with an opening through which said thrust member extends, whereby it is guided in an endwise direction.

7. The combination with a casing, having a valve opening through which fluid passes and a valve for said valve opening, of means for operating said valve, said operating means including two members one carried 75 by the other member and each having operative connection with said casing, the last mentioned member having a body portion formed with an opening, a lever carried by one member, a link between the other member and said lever, and a thrust member pivotally connected to said lever and extending through the opening in one of said members 80 and guided thereby and arranged to be actuated by said lever to unseat said valve.

8. The combination with a casing having a valve opening through which fluid passes and a valve for said valve opening, of means for operating said valve, said operating means including two members one operatively connected to the other member and each having operative connection with said casing, a lever carried by one member, a link between the other member and said lever, and a thrust member arranged to be actuated by 90 said lever to unseat said valve.

9. In mechanism of the class described, the combination with a casing, having an opening through which fluid passes forming a valve seat, and a valve for said valve seat, of means for operating said valve, said operating means including two members one operatively connected to the other member and each having operative connection with said casing, a lever carried by one member, a link between the other member and said lever, and a thrust member pivotally connected at its lower end to said lever and arranged to be actuated by the latter in an endwise direction substantially axially of the valve seat.

10. A mechanism as claimed in claim 1 in which said thrust means comprise a pivoted stem, said spring surrounding said stem and

seat, and a coiled spring carried by the upper portion of said thrust member and arranged to be compressed by the valve as the thrust member moves upwardly, whereby the 5 valve is unseated relatively quickly after the spring tension overcomes the resistance maintaining the valve on its seat.

10. A mechanism as claimed in claim 9 in which the casing is provided with guides disposed concentrically to the axis of the valve 10 seat and extend parallel thereto.

11. In a mechanism of the class described, the combination with a valve mechanism having a valve seat and a guided valve element 15 arranged to engage and disengage therewith, a swingable lever, a thermostat element for swinging said lever, and thrust means mounted on said lever and actuated thereby, said thrust means having a spring

arranged to engage with said valve element 20 and be compressed thereby as it moves in a direction to unseat said element, said thrust means being pivoted to said lever whereby said spring is free to move relative to said lever and accommodates itself to the valve 25 element during swinging movement of said lever.

12. A mechanism as claimed in claim 11, in which the spring is detachably supported on the thrust means. 30

13. A mechanism as claimed in claim 1 in which the upper end of the spring is shaped to carry the valve element after the latter is unseated.

In testimony whereof, I have hereunto 35 signed my name.

CARL M. YODER.
